UNITED STATES PATENT OFFICE.

FREDRICK SARBACH, OF WESTPARK, OHIO.

DESIGN FOR A TROLLEY-HARP.

SPECIFICATION forming part of Design No. 34,451, dated April 30, 1901.

Application filed April 1, 1901. Serial No. 53,962. Term of patent 14 years.

To all whom it may concern:

Be it known that I, FREDRICK SARBACH, a citizen of the United States, residing at Westpark, in the county of Cuyahoga and State of Ohio, have invented and produced a new and original Design for a Trolley-Harp; and I do hereby declare the following to be a full, clear, and exact description of the same, reference being had to the accompanying drawing, forming a part thereof.

This invention relates to a new and original design for a trolley-harp.

The design is clearly illustrated in the accompanying drawing, wherein the figure is a perspective view thereof.

The design comprises a stem portion A, connected by a bent or curved portion a with oppositely-disposed arms B B'. These arms for a portion of their upper surface are plain, as at b, and extended forwardly to the shoulder b', connecting the same with the portion

b². Substantially semicircular members C connect the portion b² with the extensions b³. Around the lower edge of the members b b² is a bead D.

The essential feature of the design is the stem provided with oppositely-disposed arms occupying an angle relative thereto and provided near their outer ends with the substantially semicircular curved portions.

Having thus described the invention, what is claimed as new, and desired to be secured by Letters Patent, is—

The design for a trolley-harp substantially as herein shown and described.

In testimony whereof I affix my signature in presence of two witnesses.

FREDRICK SARBACH.
